APPARATUS FOR TREATING LIQUID-SOLIDS MIXTURES

Emil C. Zitkowski, San Miguel, Tarlac, P. I.

Application July 1, 1940, Serial No. 343,372

6 Claims. (Cl. 23—270)

This invention relates to counter-current decantation and apparatus for performing the same, and more particularly relates to counter-current decantation operations employed in the sugar refining process.

In the manufacture of sugar, precipitates are formed in the purification stages. While the extraction requires the separation of the liquids and solids, there is a considerable quantity of sugar content in the form of solution adhering to the precipitates at the separation stage. To prevent losses otherwise occurring, a countercurrent decantation operation has been employed in which the solid content is washed to recover therefrom as much as possible of the adhering solution.

While various means may be employed for effecting such separations, clarifying tanks or thickeners have been used extensively for this purpose. Some thickeners may be of the washing, multi-tray type in which a descending bed of solids is subjected to washing by a rising column of liquid in limited areas, usually wells, provided for this purpose. As such apparatus requires a quiescent treatment zone for promotion of settling, the washing action, of necessity, must be conducted in such a limited way as to avoid widespread agitation.

As a consequence, the operations heretofore employed in the art have not brought the washing liquid in direct contact with any great amount of the surfaces of the solids content in order to prevent disturbance of the sludge bed.

It is an object of the present invention to provide a countercurrent decantation operation in which a sludge bed is divided between its zone of formation and its point of discharge and subjected at the point of division to thorough penetration by a countercurrent flow of washing liquid.

Another object of the invention is the provision of means for dividing a sludge bed during its gravitational descent through a settling zone to expose surfaces of the solids content to washing influences without producing undue agitation.

A further object of the invention is the provision of a zone of contact of relatively large superficial area for co-mingling streams of material in a countercurrent decantation operation.

Other objects reside in novel combinations and arrangements of parts and novel steps and treatments, all of which will appear more fully in the course of the following description.

To afford a better understanding, reference is made to the accompanying drawings illustrating

apparatus embodying features of the present invention. In the drawings, in the several views of which like parts have been designated similarly:

5 Figure 1 is a vertical central section through thickener apparatus embodying features of the present invention;

10 Figure 2 is an enlarged fragmentary view of the deck or partition dividing the tank of Figure 1 into a plurality of compartments;

Figure 3 is a section taken along the line 3—3 of Figure 1; and

Figure 4 is a section taken along the line 4—4 of Figure 1.

15 Referring first to Figure 1, settling apparatus of the thickener type has been designated generally by the reference numeral 5 and comprises a tank divided by a partition 6 into lower and upper settling compartments 7 and 8 respectively. The bottom of the tank preferably is inclined and terminates in a conical sump portion 9 having a discharge outlet 10 at its lower end.

20 A rotary shaft 12 supported in bearings 13 and 14 at its upper and lower ends carries rake elements 15 and 16 respectively. A feed well 17 is provided in the upper portion of compartment 8 for the reception of feed delivered through any suitable conduit, such as the chute 18. A launder 19 extends around the upper edge of tank 5 for the reception of solution overflowing its top, and a suitable discharge outlet 20 is provided for the removal of clear liquid collected in the launder. A suitable manhole and fluid-tight cover 21 is provided in compartment 7 to permit access thereto for cleaning or repair.

25 Shaft 12 is driven by any suitable mechanism, here illustrated as a gear 22 driven through the intermediary of a pulley 23 connected with a suitable prime mover, not shown. It will be apparent to those skilled in the art that any suitable form of driving mechanism may be employed, and if desired, elevating mechanism of the type usually associated with thickeners may be provided for elevating the rakes when starting up after shutdowns. Preferably, such mechanism will be mounted on superstructure indicated generally by the reference numeral 24.

30 The shaft 12 is hollow and has at its upper end a reservoir 25 to admit wash liquid to the hollow interior. A valve 26 is provided to regulate the flow from reservoir 25, and a discharge nozzle 27 extends laterally from shaft 12 immediately below deck 6.

35 With this arrangement, wash liquid is discharged into the upper portion of the fluid body

in compartment 7 at a sufficient velocity to move it to the periphery of deck 6 without interruption. However, the control of velocity is necessary to prevent undue turbulence, for which reason the valve 26 is provided as a means of controlling such flow.

The deck or partition 6 is fitted in close proximity to shaft 12 to prevent the passage of material from one compartment to the other centrally of the tank. Preferably, a stuffing box will be provided for this purpose. The partition 6 terminates in spaced relation to the walls of tank 5, as indicated by the reference numeral 28. The periphery of deck or partition 6 is serrated, as shown at 29, in Figure 2, and in conjunction with space 28, provides an irregularly shaped passage through which sludge moving downwardly along deck 6 must pass to enter compartment 7.

This irregularly shaped passage serves to break up and loosen the descending bed of sludge without producing an undue amount of agitation, and the wash liquid flowing from nozzle 27 toward the periphery of tank 5 rises through the descending solids coming in contact with substantially all the surfaces thereof by reason of the loosened character of the sludge body.

In order to provide for a progressive movement of settled solids, the rakes 15 and 16 are provided with suitable scraping blades 30 to act on the bed of solids deposited along the bottom surfaces of the respective compartments. As the solids in compartment 8 move from the center toward the periphery, whereas the solids in compartment 7 move from the periphery to the central sump 9, it is necessary to have the blades 30 of scraper 16 disposed in the direction opposite to the blades 30 of scraper 15.

To insure uniformity of overflow, the upper rim of tank 5 is provided with a serrated edge 31 of the same character as the edge 29 of deck 6. With this arrangement, channeling due to irregularities is prevented and only clarified solution overflows into launders 19 and passes to the discharge 20.

While the present invention has been illustrated in connection with a single deck, two-compartment tank, it will be obvious that where desired, the action in the first two compartments may be repeated in a second or more groups of compartments through which the sludge passes in a progressive movement. In such a multi-deck arrangement, the wash liquid entering the bottom of the tank will be required to pass alternately through peripheral and central passages in its ascending movement through the respective compartments, or in the alternative, a clear liquid withdrawal through the side of the tank might be provided in the upper portion of the second compartment from the bottom, as well as any other corresponding thereto.

While the present invention is adapted for use in a variety of treatments where countercurrent decantation is employed, it is particularly suited for use in the sugar refining process because of the character of the materials treated. The solids of the sludge being a combination of organic and inorganic substances, tend to pass into a state of suspension in liquid following any appreciable agitation, for which reason the loosening of the sludge bed has to be accomplished in a relatively gentle action to avoid turbulence.

The operation of the mechanism with refer-

ence to the treatment of a sludge containing sugar will now be described, it being understood that similar operating methods will be employed for any pulp or sludge treated in the apparatus.

5 Pulp or sludge from any suitable source (not shown) is fed into the feed well 17 of tank 5 through chute 18. On filling the compartments 7 and 8, a relatively quiescent condition is developed, with the result that solids settle through the liquid body standing in compartments 7 and 8 and form a sludge bed on the bottom of tank 5 and along deck 6.

After the sludge beds are formed, the outlet 10 is opened to permit removal of sludge and the action thereafter is continuous.

15 Shaft 12 is rotated at slow speed, causing the scrapers 15 and 16 to impart a progressive movement to the sludge beds. The sludge bed on partition 6 moves toward the periphery, while the sludge bed at the bottom of tank 5 moves centrally until discharge into sump 9 from which it passes from the tank through outlet 10.

20 During rotation of shaft 12, a wash liquid, usually water, is delivered through the shaft from reservoir 25 to outlet 27 and discharges from the nozzle at controlled velocity determined by regulation of valve 26. This wash liquid flows in the manner indicated by the directional arrows in Figure 1 to the passage 28 where it penetrates through the sludge bed, passing across the serrated edge 29 of partition 6 and in passage 28 to wash the individual solid particles and recover therefrom adhering solution having considerable sugar content.

25 As a further safeguard against turbulence in passage 28, an annular rim 32 is provided above such passage to prevent the direct descent of settling solids and at the same time requiring an undulating movement of the ascending liquid stream, insuring greater surface contact thereby in its movement through the sludge bed.

30 Upon rising through the bed of sludge, the wash liquid is free to rise directly along the sides of the tank to the serrated overflow 31, with the clarified liquid carrying the sugar content in solution passing across the overflow into launder 19 for subsequent removal from the treatment through outlet 20.

35 In this way, the solids forming the sludge bed in the upper compartment 8 are thoroughly washed during the descent into compartment 7 and the sugar content passes in solution with the wash liquid for continuous removal by overflow across serrated edge 31 into launder 19.

40 At the same time, solids already washed and relieved of the adhering sugar content move to sump 9 and thence out of the apparatus through discharge outlet 10 in a continuous action.

45 The provision of the peripheral washing zone of large superficial area and the loosening of the sludge bed from its movement over and through the serrated edge 29 serve to bring substantially all surfaces of the solids content in contact with wash liquid without producing undue turbulence in the settling zones. The valuable constituents comprising the sugar content dissolve readily in the wash liquid and pass with the same in the form of solution directly to the overflow for removal from the treatment.

50 Thus, it is apparent that a high degree of efficiency in the recovery of valuable constituents adhering to solids is attained in the operation described.

55 While such thickeners are used primarily in

the main purification stages of the sugar refining operation, it is to be understood that they also may be employed following existing gravity or vacuum thickener installations to treat the thickened sludges derived therefrom.

Likewise, in other treatments where counter-current decantation is employed, such as the cyanide treatment in metallurgical operations, the apparatus and methods described will be efficacious.

While the apparatus described and illustrated is particularly suited for attaining the objects of the present invention, it will be understood that various structural modifications may be employed within the spirit and scope of the invention. For example, the discharge of washing liquid may be accomplished by providing a pipe in place of nozzle 27, which will extend from shaft 12 a substantial distance or even adjacent the passage 28. Similarly, the velocity control of the wash liquid may be attained by means other than valve 26.

However, a low velocity flow is necessary to prevent undue turbulence resulting from the washing action, and consequently regulation of the flow of wash liquid to and through passage 28 is recommended.

Under some conditions it may be desirable for this purpose to eliminate the outlet through nozzle 27 and substitute a plurality of restricted discharge outlets in the shaft 12 immediately below deck 6. Preferably, these outlets will be spaced ninety degrees about the shaft, although the number and location may be varied to satisfy operating requirements.

Control of the sludge removal through the provision of suitable pumps is within contemplation of the invention and it will be apparent to those skilled in the art that regulation of discharge to balance feed is necessary in connection with continuous operation.

The number and arrangement of scraper arms will be a matter of choice, as well as the position and arrangement of blades on the scraper elements.

Where the expressions "break up" or "breaking" are used in the description and claims, they are intended to designate an action in which the continuity of matter is destroyed rather than to suggest a violent severance.

What I claim and desire to secure by Letters Patent is:

1. Apparatus of the character described, comprising a tank, a partition in the tank dividing the same into a plurality of superposed settling compartments and spaced from the sides of the tank to provide a peripheral passage, means for delivering a liquid-solids mixture into the upper compartment of the tank, means for removing clear solution from the upper portion of the tank, means for removing settled solids from the lower portion of the tank, means for moving solids settling into the upper compartment to the peripheral passage, said partition having radially projecting serrations at its periphery for breaking the solids body descending into the peripheral passage and thereby exposing the individual surfaces of the solids constituents, and means for discharging wash liquid into the lower compartment in a position to rise through the peripheral passage countercurrent to the separated solids descending therethrough.

2. Apparatus of the character described, comprising a tank, a partition in the tank dividing

the same into a plurality of superposed settling compartments and spaced from the sides of the tank to provide a peripheral passage, means for delivering a liquid-solids mixture into the upper compartment of the tank, means for removing clear solution from the upper portion of the tank, means for removing settled solids from the lower portion of the tank, means for moving solids settling into the upper compartment to the peripheral passage, said partition having radially projecting serrations at its periphery for breaking the solids body descending into the peripheral passage and thereby exposing the individual surfaces of the solids constituents, means for discharging wash liquid into the lower compartment in a position to rise through the peripheral passage countercurrent to the separated solids descending therethrough, and means for regulating the velocity of the wash liquid so introduced into said lower compartment.

3. Apparatus of the character described, comprising a tank, a partition in the tank dividing the same into a plurality of superposed settling compartments and spaced from the sides of the tank to provide a peripheral passage, means for delivering a liquid-solids mixture into the upper compartment of the tank, means for removing clear solution from the upper portion of the tank, means for removing settled solids from the lower portion of the tank, means for moving solids settling into the upper compartment to the peripheral passage, said partition having serrations projecting outwardly in a substantially horizontal direction at its periphery for breaking the solids body descending into the peripheral passage and thereby exposing the individual surfaces of the solids constituents, and means for discharging wash liquid into the lower compartment in a position to rise through the peripheral passage countercurrent to the separated solids descending therethrough.

4. Apparatus of the character described, comprising a tank, a partition in the tank dividing the same into a plurality of superposed settling compartments and spaced from the sides of the tank to provide a peripheral passage, means for delivering a liquid-solids mixture into the upper compartment of the tank, means for removing clear solution from the upper portion of the tank, means for removing settled solids from the lower portion of the tank, a scraping element for moving solids settled in the upper compartment to the peripheral passage, a scraping element for moving settled solids in the lower compartment to the solids removal means, said partition having radially projecting serrations at its periphery for breaking the solids body descending to the peripheral passage and thereby exposing the individual surfaces of the solids constituents, means for discharging wash liquid into the lower compartment in a position to rise through the peripheral passages countercurrent to solids descending therethrough, and blades disposed on the scraping elements in the respective compartments with the blades in the upper compartment directed oppositely to those in the lower compartment.

5. Apparatus of the character described, comprising a tank, a conical partition in the tank dividing the same into a plurality of superposed settling compartments and spaced from the sides of the tank to provide a peripheral passage, means for delivering a liquid-solids mixture into the upper compartment of the tank, means for removing clear solution from the upper portion of

the tank, the bottom of the tank providing the collecting surface for the lower compartment being in the form of an inverted cone, means for removing settled solids from the lower portion of the tank, means for moving solids settling into the upper compartment to the peripheral passage, said partition having radially projecting serrations at its periphery for breaking the solids body descending into the peripheral passage and thereby exposing the individual surfaces of the solids constituents, and means for discharging wash liquid into the lower compartment in a position to rise through the peripheral passage countercurrent to the separated solids descending therethrough.

6. Apparatus of the character described, comprising a tank, a partition in the tank dividing the same into a plurality of superposed settling compartments and spaced from the sides of the tank to provide a peripheral passage, means for

delivering a liquid-solids mixture into the upper compartment of the tank, means for removing clear solution from the upper portion of the tank, means for removing settled solids from the lower portion of the tank, a hollow rotary shaft in the tank, means mounted on said shaft for moving solids settling in the upper compartment to the peripheral passage, said partition having radially projecting serrations at its periphery for breaking the solids body descending into the peripheral passage and thereby exposing the individual surfaces of the solids constituents, said hollow shaft having a discharge outlet positioned in the lower compartment to direct a wash liquid into the peripheral passage countercurrent to the separated solids descending therethrough, and means for supplying wash liquid to said hollow shaft.

EMIL C. ZITKOWSKI.
